UNITED STATES PATENT OFFICE

93,939

DESIGN FOR AN AUTOMOBILE HEATER

Mathew J. Marty and Richard H. Hausse,
Chicago, Ill.

Application September 21, 1934, Serial No. 53,356

Term of patent 7 years

To all whom it may concern:

Be it known that we, MATHEW J. MARTY and RICHARD H. HAUSSE, both citizens of the United States of America, residing at Chicago, in the county of Cook and State of Illinois, have invented a new, original, and ornamental Design for an Automobile Heater, of which the following is a specification, reference being had to the accompanying drawing, forming a part hereof.

In the drawing:

Figure 1 is a view in front elevation, showing our new design.

Figure 2 is a view in vertical side elevation, showing our new design.

Figure 3 is a view looking down at the top of our new design.

Our design is of polygonal shape in front ele-

vation with rounded corners, and the central portion is of toric shape. The central portion is circular in outline. There are embossments above and below the central portion on which are distinguishable shoulders and ribs that appear to be continuous in the manner of a column interrupted by the central portion. The surface of the front slopes away from the central portion to present continuations of the central toric shape.

What we claim is:

The ornamental design for an automobile heater, as shown and described.

Signed at Chicago, Cook County, Illinois, the 17th day of September, 1934.

MATHEW J. MARTY.
RICHARD H. HAUSSE.
